222,508

MULTI-PURPOSE POCKET MAGNIFIER

Jacob Krebs, 2445 Fairmount Ave.,
Philadelphia, Pa. 19130

Filed Nov. 23, 1970, Ser. No. 26,123

Term of patent 3½ years

Int. Cl. D16—08

U.S. Cl. D57—1

FIG. 1

FIG. 2

FIG. 3

FIG. 4

FIG. 5

FIG. 1 is a perspective view of a multi-purpose pocket magnifier showing my design;

FIG. 2 is a front elevation thereof;

FIG. 3 is a rear elevation thereof;

FIG. 4 is a side elevation thereof;

FIG. 5 is an end elevation thereof;

I claim:

The ornamental design for a multi-purpose pocket magnifier, as shown.
